UNITED STATES PATENT OFFICE

2,119,847

COILING DEVICE

Karl Grube, Cleveland, Ohio, assignor to The American Steel and Wire Company of New Jersey, a corporation of New Jersey

Application December 13, 1935, Serial No. 54,309

6 Claims. (Cl. 242—54)

This invention relates to coiling devices and more particularly those which are adapted to handle continuous measured lengths of rope and the like.

It is among the objects of the invention to provide a novel coiling device which will operate to form a continuous and measured length of rope or the like into a plurality of connected coils, each of which is moved, after it is formed, to a storing position preparatory to the formation of the next succeeding coil.

Another object is the provision of a device of the class described which is easy and inexpensive to manufacture and operate.

Other objects will be apparent after referring to the drawings, in which:

Figure 1 is a sectional view of the device of the invention.

Figure 2 is an end view on the line II—II of Figure 1.

Figure 3 is a sectional view on the line III—III of Figure 1.

Referring more particularly to the drawings, the numerals 2 and 3 designate two parts of a sectional drum, the former of which is of substantially heavier construction. The part 2 of the sectional drum is provided with a centrally disposed and integral arbor 4 having a central bore in order that it may be mounted on a suitably driven shaft 7 which is journaled, as at 8, on an adjacent support 9. The arbor 4 and shaft 7 are keyed together, as shown at 10.

The end of the part 2 of the drum which is remote from the part 3 carries an irregularly shaped flange 11, on the outer face of which there is pivoted, as at 13, a plurality of levers 14. Due to the irregular shape of the flange 11, a plurality of spaced recesses 12 are provided for a purpose to be later described. Each of these levers 14 is V-shaped, providing a remote extension 15 which extends through an aperture 16 in the face of the part 2 of the drum. These extensions 15 of the levers 14 combine with the irregularly shaped flange 11 to provide a coiling recess 17.

A clutch element 18 is slidably mounted on the shaft 7 and provides a conical face 19 and a flat and annular surface 20 of greater diameter. The bottoms of the outer surfaces of the V-shaped levers 14 provide surfaces 21 which are adapted to move into and out of contact with the conical face 19 and flat surface 20 of the clutch element 18. The contact surfaces 21 of the levers 14 are resiliently maintained against the clutch element 18 by a continuous coil spring 23 which is maintained in the valleys of the V's of the levers.

The end of the clutch element 18 which is remote from the arbor 4 is provided with a groove 24 in which there is carried a clutch collar 25. A lever 27 is pivoted on one of its ends, as at 28, to the support 9. The intermediate portion of the lever 27 is connected, as at 29, to the clutch collar 25.

According to the foregoing construction and arrangement of parts, a rope X is led from a suitable measuring machine onto the part 2 of the sectional drum and into the coiling guide 17 provided by the irregularly shaped flange 11 and extensions 15 of the V-shaped levers 14. The shaft 7 is rotated until a coil of required length is formed in the coiling guide 17, and is then stopped in any suitable manner. During this stage of operation the lever 27 was in the solid line position of Figure 1.

The coil so formed is tied with band wires (not shown) which are applied through the recesses 12 in the irregularly shaped flange 11, and the coil suitably labeled. The lever 27 is then moved to the dotted line position of Figure 1, which withdraws the extensions 15 of the V-shaped levers 14 and permits the coil to be moved (in any suitable manner) from right to left. The lever 27 is then moved to the solid line position of Figure 1, which causes the surfaces 21 on the V-shaped levers 14 to ride over the conical face 19 and onto the flat and annular surface 20 of the clutch element 18. This movement of the elements restores the extensions 15 of the V-shaped levers to their former positions (extending through the apertures 16 in the part 2 of the sectional drum). The shaft 7 is again rotated and another coil formed in the coiling recess 17 provided by the irregularly shaped flange 11 and the extensions 15 of the V-shaped levers 14. As the sequences of the operation are repeated, a plurality of interconnected and separated formed coils X are stored on the part 3 of the sectional drum.

A spider 30 is carried on the end of the part 3 of the sectional drum which is remote from the part 2. This spider 30 is centrally bored, as at 31, to receive a shaft 32 which is threaded on its end, and which is held on the spider by a nut 33. A collar 34 which carries a plurality of integrally-formed cam-faces 35 is rotatably mounted on the shaft 32. The collar 34 is also provided with a knurled knob 36 for enabling its easy rotation. Each of the arms of the spider 30 carries a radially reciprocable finger 37 which has an enlarged head 38 on its inner end. Each of these radially reciprocable fingers 37 is biased

inwardly by a coil spring 38 with its enlarged head 38 in contact with one of the cam-faces 35 on the collar 34. By partially rotating the sleeve 34 the fingers 37 may be radially moved through apertures 40 in the part 3 of the sectional drum to prevent the movement of the stored coils X therefrom.

While I have shown and described one specific embodiment of my invention, it will be understood that I do not wish to be limited exactly thereto, since various modifications may be made without departing from the scope of my invention, as defined by the following claims.

I claim:

- 15 1. A coiling device comprising an elongated drum carrying a radial flange, fingers pivotally connected to said flange adapted to extend radially out of said drum to cooperate with said flange in forming a coiling groove, secondary fingers 20 adapted to extend radially out of said drum to prevent the movement of a coil therefrom, said secondary fingers being substantially spaced from said first named fingers, and means for moving said first named fingers and said secondary fingers into and out of said drum.
- 25 2. A coiling device comprising an elongated drum carrying a radial flange, fingers pivotally connected to said flange adapted to extend radially out of said drum to cooperate with said flange in forming a coiling groove, secondary fingers 30 adapted to extend radially out of said drum to prevent the movement of a coil therefrom, said secondary fingers being substantially spaced from said first named fingers, and independent 35 means for moving said first named fingers and said secondary fingers into and out of said drum.
3. In a coiling device including a drum having an irregularly shaped flange formed on one end thereof, a plurality of V-shaped levers pivotally 40 secured to said flange, a clutch engaging the apexes of said V-shaped levers, means for operating said clutch to advance said levers through said drum, said levers when advanced through said drum cooperating with said flange to form 45 a coiling recess, and means carried by said levers adapted to retract said levers when said clutch is moved horizontally whereby said coiled wire is capable of being moved horizontally along said drum.

4. In a coiling device including a drum having an irregularly shaped flange formed on one end thereof, a plurality of V-shaped levers pivotally secured to said flange, a clutch engaging the apexes of said V-shaped levers, means for operating said clutch to advance said levers through said drum, said levers when advanced through said drum cooperating with said flange to form a coiling recess, means carried by said levers adapted to retract said levers when said clutch is moved horizontally whereby said coiled wire is capable of being moved horizontally along said drum, and means on the opposite end of said drum to prevent movement of the stored coils therefrom.

5. In a coiling device including a drum having an irregularly shaped flange formed on one end thereof, a plurality of V-shaped levers pivotally secured to said flange, a clutch engaging the apexes of said V-shaped levers, means for operating said clutch to advance said levers through said drum, said levers when advanced through said drum cooperating with said flange to form a coiling recess, means carried by said levers adapted to retract said levers when said clutch is moved horizontally whereby said coiled wire is capable of being moved horizontally along said drum, and means on the opposite end of said drum to prevent movement of the stored coils therefrom, said means including means adapted to permit removal of said coil from said drum.

6. A coiling device comprising an elongated drum carrying an irregularly shaped flange, an integral centrally disposed arbor on said drum, a shaft extending through said arbor for rotating said drum, a plurality of V-shaped levers pivotally supported by said flange, a clutch member slidably mounted on said shaft and provided with a conical face and a flat annular surface, said clutch adapted to advance said levers through said drum to cooperate with said flange to form a coiling recess, and means carried by said levers adapted to retract said levers through said drum when the flat surface of said clutch is moved out of contact with said levers to permit said coiled wire to be moved along said drum.

KARL GRUBE.
